(57) **CLAIM**

The ornamental design for an antenna base, as shown and described.

DESCRIPTION

FIG. 1 is a front elevational view of an antenna base showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is another perspective view thereof;

FIG. 10 is a perspective view of the antenna base in use; and, FIG. 11 is another perspective view of the antenna base in use.

The broken lines illustrate portions of the antenna base which form no part of the claimed design.
